GEORGE H. LINCOLN, OF PROVIDENCE, RHODE ISLAND, ASSIGNOR TO
THE LINCOLN MANUFACTURING COMPANY, OF SAME PLACE.

Design No. 2,569, dated February 5, 1867.

DESIGN FOR A TRADE-MARK.

The Schedule referred to in these Letters Patent and making part of the same.

TO ALL WHOM IT MAY CONCERN:

Be it known that I, GEORGE H. LINCOLN, of the city and county of Providence, in the State of Rhode Island, have originated and designed a new Design for a Trade-Mark Label, of which the following is a full, clear, and exact description, reference being had to the accompanying specimen, making a part of this specification.

The design is intended for a label to distinguish a special variety of soap, and may be pasted upon the boxes or packages containing the article, or be impressed upon the bars or cakes of the soap. It consists of a central picture of the traditional Diedrich Knickerbocker, as that personage is commonly represented while in meditation over the composition of his "History of New York from the Beginning of the World to the End of the Dutch Dynasty." Above the engraving is the word "Knickerbocker," and underneath the same, the word "soap," expressive of the brand by which the article is to be known; while upon the scroll upon the left-hand side of the label are the words "Lincoln Mfg. Co.;" and upon a similar scroll upon the right-hand side are the words "Providence, R. I."

What I claim as my invention, and desire to secure by Letters Patent, is—

The design for a trade-mark, herein shown and described.

GEORGE H. LINCOLN.
